UNITED STATES PATENT OFFICE

JAMES H. REINHARDT, OF EAST ORANGE, NEW JERSEY, ASSIGNOR TO AMERICAN BANK
NOTE COMPANY, OF NEW YORK, N. Y., A CORPORATION OF NEW YORK

NUMBERING HEAD

Application filed November 13, 1929. Serial No. 406,867.

The invention relates to a numbering head of the type in which the units digit wheels of a plurality of associated heads receive a timely positive actuation by mechanisms incorporated in the numbering machine proper and more particularly to a head of this type in which the digit wheels of each unit in the head may be adjusted in relation to a shaft actuating mechanism operative upon the units wheels, so as to permit relative adjustment of the digit wheels of different units actuated from the same shaft.

A numbering head has heretofore been devised by me in which each of the three wheels of lower denomination has been actuated by a shaft common to all wheels of the same denomination in a row of numbering head units, but with this construction of head, it was essential that all units of a row be in exact alignment.

In order to provide a numbering head of the type to which my invention relates, which may be adapted to a class of work wherein exact alignment of different numbering head units of a group is not necessary, or wherein by reason of paper shrinkage or conditions in a printing plate, various corresponding designs are not accurately aligned, I so construct the numbering head of my present invention that, notwithstanding that the same shaft is utilized to actuate the unit wheels of all the units in a row, the digit wheels of any unit may be adjusted to a position out of alignment with the wheels of other units actuated from the same shaft. In attaining the object of the invention, it is essential that the main frame of each numbering head unit and the frame carrying the digit wheels be independent, one of the other, and that the actuating mechanism and the transfer mechanism be carried by the main frame of the unit, while the gear wheels for actuating the several digit wheels are actuated through intermediate gearing so constructed and arranged as to retain their operative relation to each other notwithstanding the movement of the frame carrying the digit wheels and some of the gears of each train.

I also provide, in connection with the mechanisms above referred to, a straighten-

ing mechanism operative upon the various digit wheels of each unit, this mechanism including an actuating member common to all units in a row, so as to permit the adjustment of the various numbering units in a row, in relation to each other and also longitudinally of the machine cylinder.

I also provide in the numbering head of my invention, means whereby rotary movement of the various digit wheels, during their adjustment toward and from the actuating shaft of the head, may be prevented to avoid the characters being moved to an improper printing position, or if desired, to cause movement of the digit wheels to correct this condition. This mechanism applies only to the wheels which are automatically actuated during the operation of the machine and does not apply to wheels of higher denomination ordinarily not so actuated.

In a numbering unit of the invention, the various actuating and transfer mechanisms, excepting the aligning mechanism, may be located at one side of the digit wheels and between the side frames of the unit, thus permitting a close setting of the digit wheels and the desired strength in, and location of, the various parts of the actuating mechanisms. This construction applies both to the gears mounted upon the main actuating shaft and to the transfer mechanisms actuated thereby, mounted upon a shaft carried by the main frame of the machine, as well as to the intermediate gearing for imparting movement to the digit wheels.

The invention consists in the novel features of construction and combination of parts hereinafter set forth and described, and more particularly pointed out in the claims hereto appended.

Referring to the drawings,

means for the aligning or straightening cam
shaft.

Like numerals refer to like parts through-
out the several views.

The numbering head of the invention is
adapted for use with a special type of num-
bering machine in which a large gear 10
receives a timely intermittent actuation
through mechanisms in the numbering ma-
chine, not shown. The extent of movement
of this gear 10 is such that with each actua-
tion thereof, the units digit wheel of each
numbering head unit mounted upon the cyl-
inder 11 of the numbering machine, will re-
ceive one-tenth of a revolution.

Since each numbering head is identical
with every other and since each unit embod-
ied in a numbering head is the same as every
other unit, a description of but one number-
ing head and one unit will be given.

The numbering head of the invention in-
cludes a bridge proper 13 having a fixed
clamp member 14 and a movable clamp mem-
ber 15, these clamp members being closed
upon the overhanging edges of the cylinder
11 by means of a tie bolt 16. The upper face
of the bridge member 13 is provided with an
undercut or dove-tailed, slideway 17.

Carried by the bridge member 13, are re-
movable end brackets 18 and 19 mounted
upon the slideway 17 and secured in relation
thereto in any desired manner.

Mounted in the end brackets 18 and 19 is an
actuated shaft 20 having idly mounted
thereon a small gear 21 by means of which
construction, the shaft 20, as will appear
hereinafter, is utilized to simultaneously ac-
tuate all units digit wheels of the various
numbering head units embodied in the num-
bering head. The gear wheel 21 is connected
to the shaft 20 by means of a clutch mecha-
nism 22 for the purpose of permitting ad-
justment of the bridge 13 circumferentially
of the member 11. This clutch mechanism
may also be used when setting the digit
wheels of the various numbering head units
out of alignment one with the other.

It is to be understood that in the number-
ing head of my invention there are a plural-
ity of units carried by each bridge member,
spaced apart at various intervals so as to en-
sure the placing of the imprint in the proper
position upon a previously printed sheet, and

that in so spacing the various numbering
head units they have movement longitudi-
nally of the bridge member 13 and of the ac-
tuating shaft 20, as well as circumferentially
of the cylinder 11.

I will now describe one of the numbering
head units. This unit comprises a main
frame 23 having a base undercut so as to seat
upon the slideway 17. This frame 23 has end
plates 24 and 25 having bearings for the shaft
20. The tops of these end plates 24 and 25
overhang the end plates as shown at 26, Fig.
4, and preferably are curved, concentric with
the axis of the cylinder 11.

Each numbering head unit may have a sin-
gle set of digit wheels, or twin sets, as de-
sired, and the number of wheels of each set
may be varied as desired. The nature of the
characters upon each digit wheel may be arbi-
trarily determined, which is usual in the art,
some of the wheels being used for digits, and
others being used for emblems or key letters.
In the form of the invention shown, seven
wheels are used, the units wheel being num-
bered 27, the tens 28, the hundreds 29, and
each of the wheels of still higher denomina-
tion, 30.

The arrangement or sequence of the char-
acters or digits upon the corresponding
wheels of both sets in a unit and on each set
is the same.

The wheels 30 are hand set and not auto-
matically actuated. The wheels 27, 28 and 29
are mechanically and automatically actuated
with the progressive actuation of the num-
bering machine. The wheels 30 are idly
mounted upon a shaft 31 fixed in a digit
wheel or U-frame 32, which frame is capable
of adjustment toward and from the end
plates 24 and 25 of the unit, and is held in
any adjusted position by means of set screws
33-34 mounted in overhangs 26 of the end
plates 24-25 of the main frame of the unit.

The hundreds wheel 29 is carried by a
sleeve 35 also idly mounted upon the shaft
31, this shaft being reduced in diameter at
points as shown in Fig. 3, merely for the pur-
pose of reducing the bearing areas. The tens
wheel 28 is carried by a shorter sleeve 36
bearing upon portions of the sleeve 35, while
the units wheel is carried by a sleeve 37 bear-
ing upon portions of the sleeve 36. The
sleeves 35, 36 and 37 are, therefore, co-axial
and nested, being of different lengths in
order to permit the application of power
thereto for turning the respective number-
ing wheels. The sleeve 37 and its digit wheel
27 are actuated through a gear 38 secured to
the sleeve 37, while the digit wheels 28 and

29 are actuated through the gears 39 and 40
secured respectively to the sleeves 36 and 35.
Power from the shaft 20 is applied through
suitable gears to the gear 38, and is applied,
indirectly, through transfer mechanisms to

130

the gears 39 and 40. This will now be described.

Splined or otherwise adjustably connected with the shaft 20 is a gear 41 entrained through the intermediate gear 42, with the gear 38, so that with each impulse of the shaft 20, the sleeve 37 and units digit wheel 27 will receive one-tenth of a rotation. Carried by the gear 41, is a single tooth gear 43 co-operating with a Geneva stop gear 44 carried by a sleeve 45 and idly mounted upon a shaft 46. The sleeve 45 carries a gear 47 enmeshed with an idler gear 48 on the shaft 20, which in turn is entrained with the gear 39 through an intermediate gear 49.

The gear 48 in turn carries a single tooth gear 50 of a Geneva stop movement, the co-operating gear 51 of which is mounted upon a sleeve 52 carrying a gear 53 entrained with the gear 40 through a gear 54 idly mounted upon the shaft 20, and an intermediate gear 55. By the use of transfer mechanisms and gear trains as described, the progressive actuation of the units, tens and hundreds wheels 25 is secured. The various gear trains and transfer mechanisms heretofore described are located at one side of the U-frame 32, being separated from the digit wheel by means of a partition 56 providing bearings for the 30 sleeve 37, and the shaft 20, and supporting the shaft 46 upon which the driven members of the Geneva stop movement are mounted. This locating of the actuating mechanisms of the digit wheels at one side of the digit 35 wheels permits the various gears to be substantially made, and also affords the proper clearance for the locating of these parts.

The various driven members of the Geneva stop mechanism are idly mounted upon the 40 shaft 46. The intermediate gears 42, 49 and 55 are idly mounted upon a shaft carried by a link mechanism which will be referred to in connection with the adjustment of the U-frames 32 and the digit wheels carried 45 thereby. The shaft 31 is a fixed shaft upon which the various sleeves and digit wheels are idly mounted. The only shaft which turns is the shaft 20, and this shaft is common to all digit wheel units carried by the 50 bridge 13.

Whether a single set of digit wheels or twin sets are used in each unit, it may be necessary to move the digit wheels of a set toward or from the shaft 20 in order to properly space the number in relation to the design on printed sheets. This may be due to conditions incidental to the preparation of the plate from which these sheets are printed, or to shrinkage of the paper after printing. In small work it is more likely to occur than in larger work.

To thus throw the digit wheels of the sets of one unit out of alignment with the set of digit wheels of another unit acted on by the 60 same actuating shaft 20, it is merely necessary

to move the U-frame 32 upon the base of the main frame 23 of the unit, the set screw 33 being released to permit this movement of the frame 32 and tightened after such movement. The upper face of the base of the main frame 70 23 is curved upon a radius of the axis of the cylinder 11, as is also the tops of the U-frame 32.

Since the various digit wheels, the shaft and gears for actuating same and the intermediate gears for transmitting power thereto from the shaft 20, have movement with the U-frame, it is obvious that this movement of the U-frame would disturb their operative relation were means not provided to maintain 75 this operative relation, irrespective of movement of the U-frame either toward or from said shaft 20. In the form of the invention shown, I maintain the desired operative relation of the gears of each train, by supporting a shaft 57 from links 58 and 59, mounted respectively upon the shafts 20 and 31, said shaft 57 being rotatable in one of said links. By the use of these links 58 and 59, the shaft 57 is permitted to have movement circumferentially of the shaft 20, and circumferentially of the shaft 31 as required by movements of the U-frame 32, and the various gears upon these shafts will always remain in mesh. A slot in an end of the U-frame 32 85 90 95 permits such movement of the shaft 57.

There is this difficulty, however. With movement of the shaft 31 with the U-frame and of the shaft 57 resulting from such movement, there would be a slight turning movement of the gears of the train, were not means provided to either prevent or correct this condition. The clutch member 22, by freeing the shaft 20 from the gear 21, will permit this shaft and the gears carried thereby and rotatable therewith, to turn freely. This would have the desired corrective action were it not for the fact that the U-frame of the different units would generally be moved to a different extent, and any movement of the gears carried by the shaft 20 would, in itself, have the result of rotating all of the units wheels to the same extent irrespective of such differential movement of the different U-frames. 100 105 110 115

So far as those gears which are idly mounted upon the shaft 20 are concerned, no difficulties arise, since the use of a Geneva stop, after the first actuation thereof, will restore a proper timing in the actuation of the various digit wheels in case such is destroyed by a slight movement of the single tooth member of the Geneva stop mechanism as the result of the movement of the U-frame and of the intermediate gears carried thereby. To further correct the condition, however, I connect the gears 38, 39 and 40 with their respective sleeves 37, 36 and 35 by means of a shoddered-member 60 carried by each of said sleeves, and a member 61 carried by each of 120 125 130

said gear wheels, the connection between the members 60 and 61 being by means of adjusting screws 62 which may not only be utilized to turn the digit wheels actuated through the 5 gears 38, 39 and 40 entirely independently of said gears, but will permit the turning of the gears entirely independently of the digit wheels during movement of the U-frame 32. This last result is secured by merely releasing 10 the screws 62.

Of course, it will be understood that the quantity of the movement of the U-frame 32 will never be great, a maximum range of one-quarter to three-eighths of an inch being 15 provided for.

It is desirable to provide what is known as an aligning mechanism having the two-fold object of bringing the printing characters upon the digit wheels into alignment following each action thereof, and holding them in such alignment at all times except when it is necessary to turn the wheels.

With the type of numbering head herein described, this alignment mechanism prevents considerable difficulty. The numbering head is capable of adjustment as a unit circumferentially of the cylinder 11. The various numbering head units of each head are not only movable with the bridge member 13 about the cylinder 11, but are movable about said cylinder independently of said bridge member 13, and are also movable longitudinally of the cylinder. It is desirable to actuate this aligning or straightening mechanism from the power driving the numbering machine, thus causing its simultaneous actuation with all of the numbering head units mounted upon the same bridge. Consequently, while the aligning or straightening mechanism acts upon the various digit wheels, it is not practicable to adjust the actuating means of the aligning mechanism with the digit wheels of the set of any unit.

To meet this condition, I provide a cam shaft 63 rotatably mounted in the end frames 18 and 19 of the bridge 13. This shaft is a rocking shaft actuated in any desired manner from a cam 64 adjacent the numbering head cylinder 11. This cam 64 is of a length 50 to act simultaneously on all numbering heads upon the cylinder 11. A plunger 65, similar to that commonly used upon type high numbering heads, is mounted in each end bracket, and acts upon the cam shaft 63. The cam 64 is a fixed cam so that the plunger 65 of every 55 numbering head will engage the cylinder when it reaches a predetermined position in its revolution.

Each digit wheel of each set carries a star 60 wheel 66 having ten teeth. This applies to both the automatically, and the hand, operated wheels of the set. Mounted in each of the U-frames 32, is a series of aligning or straightening pawls 67, one co-operating with 65 each star wheel 66. These pawls may be

spring pressed if desired. The ends of the pawls are projected beyond the gears with which they co-operate, and have an elongated flattened portion 68 projecting below the cam shaft 63 and affording a length of surface 70 sufficient to permit the adjustment of the U-frame without disengaging the pawls 67 and the cam shaft 63. Where twin sets of digit wheels are used, the flattened extended portion 68 of the aligning pawls of one set 75 of wheels, laps the corresponding portion of the other set of wheels. If desired, these pawls may be acted upon by a spring 69, although this is not essential.

The operation of the herein described numbering head is substantially as follows:—

The bridge member 13, carrying two or more numbering head units, may be mounted upon, or removed from, the cylinder 11 by the use of the clamp members 14, 15 and the tie bolt 16. The shaft 20 passes through and is splined to the main actuating gear 41 of each unit. In spacing the numbering head units longitudinally of the cylinder 11, it is merely necessary to release the means for locking them on the slideway 17 and move the main frame of each unit along the shaft 20 and along the slide 17. In so adjusting the units, they will also move along the cam shaft 63. If it is desired to adjust a numbering head circumferentially of the cylinder, it is merely necessary to release the clutch 22, clamps 14 and 15 and slide the bridge member 13 about the cylinder to the desired position.

In setting the various digit wheels to the desired starting position, it is merely necessary to release the clutch 22 and the aligning or straightening pawls 67 and turn the digit wheels by hand, using a suitable tool. When the digit wheels have been set to the proper place, the clutch 22 may be re-engaged with the gear 21 and thus have the numbering head in readiness to be operated. In making trial impressions, it may be found that a true alignment of the corresponding sets of digit wheels 105 of various units upon the bridge 13 is not desirable. To correct this condition, the U-frame 32 is released and moved upon the main frame 23 of those units. Where twin sets of digit wheels are used, it will usually be found necessary to actuate both U-frames 32. The movement of these frames may differ both as to the frames of the same unit, or as to the frames in different units carried by the same bridge member.

The manner of turning the units, tens and hundreds wheels, and the operation of the Geneva stop transfer mechanism will be obvious from the foregoing description.

It is preferable, in adjusting the U-frames 125 32, to disconnect the clutch 22 and release the screws 62 so that the movement of the gear 38 and of the shaft 20 can have no effect so far as moving the units digit wheels out of alignment is concerned. It is also preferable to 130

so set the cam shaft 63 during this adjustment, as to have the alignment or straightening pawls 67 in operative relation with the respective wheels 66 to check any turning movement of the digit wheels. It is obvious that since the gears 38, 39 and 40 are free to have limited movement in relation to the digit wheels actuated thereby, as the result of the releasing of the screws 62, that any movement of said gears, resulting from the movements of the U-frame 32 or any movement of the shaft 20 when re-setting the clutch 22, can have no effect on the digit wheels. After the U-frames have been properly set, the screws 62 may be turned to again connect the gears 38, 39 and 40 with the sleeves upon which they are mounted.

When the various numbering head units have been properly adjusted and set in the manner above described, power may be applied to the machine. With each rotation of the cylinder 11 and the gear 10, the shaft 20 will receive one-tenth of a revolution as the result of the functioning of the mechanism of the machine not shown. This movement will occur substantially immediately following the making of the impression by all numbering heads on the cylinder 11, and before the first head reaches the inking mechanism. During the interval that the shaft 20 is having movement, all plungers 65 will be engaged with, and depressed by, the cam 64, thus rocking the cam shaft 63 and permitting a free movement of the various aligning or straightening pawls 67 so that the various digit wheels may turn. Immediately following the stoppage of the shaft 20, the plungers of each head will be actuated by their springs to again re-set the cam shaft, and hold said pawls against movement in relation to the star wheels, this position being maintained until following the making of the next impression.

It is not my intention to limit the invention to the precise details of construction shown in the accompanying drawings, it being apparent that such may be modified without departing from the spirit and scope of the invention. The utility of the invention is limited to a numbering head construction having a plurality of units each embodying a single or twin sets of digit wheels, the unit wheels of each set being actuated from a single shaft through entrained gears and transfer mechanisms where required, so as to permit any set of wheels in the various units to be moved toward or from the main single actuating shaft so as to destroy that accuracy of alignment secured by the use of such a shaft. This involves mechanisms for maintaining the desired operative relation of the gears in the various trains and mechanisms preventing or correcting rotation of the units digit wheels resulting from adjustment of any set of digit wheels in the various units.

Having described the invention, what I claim as new and desire to have protected by Letters Patent, is:—

1. A numbering head embodying therein a bridge member, a main actuating shaft mounted therein, a gear carried thereby, whereby said shaft may receive intermittent actuation from a co-operating gear of a numbering machine, and a plurality of numbering head units, each embodying therein a main frame, mounted upon said bridge members and adjustable thereon lengthwise of said actuating shaft, a digit wheel frame adjustable upon said main frame towards and from said actuating shaft, digit wheels mounted in said frame, a transfer mechanism, gear trains connecting said actuating shaft with the units wheel, and wheels of one denomination with wheels of another denomination through said transfer mechanism, gears of each train being movable with said digit wheel frame, and means whereby the gears of each train are held in the operative relation during and following an adjustment of said digit wheel frame.

2. A numbering head embodying therein a bridge member, a main actuating shaft mounted therein, a gear carried thereby, whereby said shaft may receive intermittent actuation from a co-operating gear of a numbering machine, and a plurality of numbering head units, each embodying therein a main frame, mounted upon said bridge members and adjustable thereon lengthwise of said actuating shaft, a digit wheel frame adjustable upon said main frame towards and from said actuating shaft, a digit wheels mounted in said frame, a transfer mechanism, gear trains connecting said actuating shaft with the units wheel, and wheels of one denomination with wheels of another denomination through said transfer mechanism, gears of each train being movable with said digit wheel frame, means whereby the gears of each train are held in the operative relation during and following an adjustment of said digit wheel frame, and means connecting the gear train operative upon the units wheel with said wheel, whereby said gear may receive movement independently of said wheel.

3. A numbering head embodying therein a bridge member, a main actuating shaft mounted therein, a gear carried thereby, whereby said shaft may receive intermittent actuation from a co-operating gear of a numbering machine, and a plurality of numbering head units, each embodying therein a main frame, mounted upon said bridge members and adjustable thereon lengthwise of said actuating shaft, a digit wheel frame adjustable upon said main frame towards and from said actuating shaft, digit wheels mounted in said frame, a transfer mechanism, gear trains connecting said actuating shaft with the units wheel, and wheels of one

denomination with wheels of another denomination through said transfer mechanism, gears of each train being movable with said digit wheel frame, means whereby the gears 5 of each train are held in the operative relation during and following an adjustment of said digit wheel frame, a star wheel carried by each digit wheel, pawls mounted in said digit wheel frame and co-operating respectively with a star wheel, a cam shaft mounted in said bridge member and co-operating with all units in a head, and means operative upon said cam shaft to permit movement of said pawls. 10

4. A numbering head embodying therein a bridge member, a main actuating shaft mounted therein, a gear carried thereby, whereby said shaft may receive intermittent actuation from a co-operating gear of a numbering machine, and a plurality of numbering head units, each embodying therein a main frame, mounted upon said bridge members and adjustable thereon lengthwise of said actuating shaft, a digit wheel frame adjustable 15 upon said main frame towards and from said actuating shaft, digit wheels mounted in said frame, a transfer mechanism, gear trains connecting said actuating shaft with the units wheel, and wheels of one denomination with wheels of another denomination through 20 said transfer mechanism, gears of each train being movable with said digit wheel frame, said gear trains and said transfer mechanism being located on the other side of said partition, nested sleeves carrying digit wheels of lower denomination, and connected respectively with the last 25 gears of a gear train, and means whereby the gears of each train are held in the operative relation during and following an adjustment of said digit wheel frame. 30

5. A numbering head embodying therein a bridge member, a main actuating shaft mounted therein, a gear carried thereby, whereby said shaft may receive intermittent actuation from a co-operating gear of a numbering machine, and a plurality of numbering head units, each embodying therein a main frame, mounted upon said bridge members and adjustable thereon lengthwise of said actuating shaft, a digit wheel actuating shaft, a partition in said frame, digit wheels mounted in said frame on one side of said partition, a transfer mechanism, gear trains connecting said actuating shaft with the units wheel, and wheels of one denomination with wheels of another denomination through 35 said transfer mechanism, gears of each train being movable with said digit wheel frame, said gear trains and said transfer mechanism being located on the other side of said partition, nested sleeves carrying digit wheels of lower denomination, and connected respectively with the last gears of a gear train, means whereby the gears of each train are held in the operative relation during and following an adjustment of said digit wheel frame, and adjustable means connecting each sleeve with the gear carried thereby, whereby said gear may receive movement independently of said sleeve. 40

6. A numbering head embodying therein a bridge member, a main actuating shaft mounted therein, a gear carried thereby, whereby said shaft may receive intermittent actuation from a co-operating gear of a numbering machine, and a plurality of numbering head units, each embodying therein a main frame, mounted upon said bridge members and adjustable thereon lengthwise of said actuating shaft, two digit wheel frames adjustable upon said main frame towards and from said actuating shaft, a set of digit wheels mounted in each of said frames, a transfer mechanism, gear trains connecting said actuating shaft with the units wheel of each set of digit wheels, and wheels of one denomination with wheels of another denomination through 45 said transfer mechanism, gears of each train being movable with a digit wheel frame, means whereby the gears of each train are held in the operative relation during and following an adjustment of a digit wheel frame, means connecting each gear train operative upon a units wheel with said wheel, whereby said gear may receive movement independently of said wheel. 50

7. A numbering head embodying therein a bridge member, a main actuating shaft mounted therein, a gear carried thereby, whereby said shaft may receive intermittent actuation from a co-operating gear of a numbering machine, and a plurality of numbering head units, each embodying therein a main frame, mounted upon said bridge members and adjustable thereon lengthwise of said actuating shaft, a digit wheel frame adjustable upon said main frame towards and from said actuating shaft, a partition in said frame, digit wheels mounted in said frame on one side of said partition, a transfer mechanism, gear trains connecting said actuating shaft with the units wheel, and wheels of one denomination with wheels of another denomination through 55 said transfer mechanism, gears of each train being movable with a digit wheel frame, means whereby the gears of each train are held in the operative relation during and following an adjustment of a digit wheel frame, means connecting each gear train operative upon a units wheel with said wheel, whereby said gear may receive movement independently of said wheel. 60

8. A numbering head embodying therein a bridge member, a main actuating shaft mounted therein, a gear carried thereby, whereby said shaft may receive intermittent actuation from a co-operating gear of a numbering machine, and a plurality of numbering head units, each embodying therein a main frame, mounted upon said bridge members and adjustable thereon lengthwise of said actuating shaft, a digit wheel frame adjustable upon said main frame towards and from said actuating shaft, a partition in said frame, digit wheels mounted in said frame on one side of said partition, a transfer mechanism, gear trains connecting said actuating shaft with the units wheel, and wheels of one denomination with wheels of another denomination through 65 said transfer mechanism, gears of each train being movable with a digit wheel frame, means whereby the gears of each train are held in the operative relation during and following an adjustment of a digit wheel frame, means connecting each gear train operative upon a units wheel with said wheel, whereby said gear may receive movement independently of said wheel. 70

of said wheel, a star wheel carried by each digit wheel, pawls mounted in each digit wheel frame and co-operating respectively with a star wheel, a cam shaft mounted in said bridge member and co-operating with the pawls operative upon the digit wheels of each set in each unit, and means operative upon said cam shaft to permit movement of said pawls.

8. A numbering head embodying therein a bridge member, a main actuating shaft mounted therein, a gear carried thereby, whereby said shaft may receive intermittent actuation from a co-operating gear of a numbering machine, and a plurality of numbering head units, each embodying therein a main frame, mounted upon said bridge members and adjustable thereon lengthwise of said actuating shaft, a digit wheel frame adjustable upon said main frame towards and from said actuating shaft, digit wheels mounted in said frame, gear trains connecting said actuating shaft with the units wheel, gear trains for progressively actuating wheels of different denominations, a Geneva stop movement in the gear trains of lower denomination, and carried by said main frame, gears of each train being movable with said digit wheel frame, means whereby the gears of each train are held in the operative relation during and following an adjustment of said digit wheel frame, a star wheel carried by each digit wheel, pawls mounted in said digit wheel frame and co-operating respectively with a star wheel, a cam shaft mounted in said bridge member and co-operating with all units in a head, and means operative upon said cam shaft to permit movement of said pawls.

9. A numbering head embodying therein a bridge member, a main actuating shaft mounted therein, a gear carried thereby, whereby said shaft may receive intermittent actuation from a co-operating gear of a numbering machine, and a plurality of numbering head units, each embodying therein a main frame, mounted upon said bridge members and adjustable thereon lengthwise of said actuating shaft, a digit wheel frame adjustable upon said main frame towards and from said actuating shaft, digit wheels mounted in said frame, a transfer mechanism, gear trains connecting said actuating shaft with the units wheel, and wheels of one denomination with wheels of another denomination through said transfer mechanism, gears of each train being movable with said digit wheel frame, and idly mounted upon a movable shaft, a digit wheel shaft, a link mounted upon said digit wheel shaft and said movable shaft, and a second link mounted upon said actuating shaft and connected with said movable shaft, whereby said digit wheel frame may be adjusted without disturbing the operative relation of the gears of each train.

10. A numbering head embodying therein a bridge member, a main actuating shaft mounted therein, a gear carried thereby, whereby said shaft may receive intermittent actuation from a co-operating gear of a numbering machine, a clutch mechanism connecting said gear with said shaft, and a plurality of numbering head units, each embodying therein a main frame, mounted upon said bridge members and adjustable thereon lengthwise of said actuating shaft, a digit wheel frame adjustable upon said main frame towards and from said actuating shaft, digit wheels mounted in said frame, a transfer mechanism, gear trains connecting said actuating shaft with the units wheel, and wheels of one denomination with wheels of another denomination through said transfer mechanism, gears of each train being movable with said digit wheel frame, means whereby the gears of each train are held in the operative relation during and following an adjustment of said digit wheel frame, means connecting the gear train operative upon the units wheel with said wheel, whereby said gear may receive movement independently of said wheel, a star wheel carried by each digit wheel, pawls mounted in said digit wheel frame and co-operating respectively with a star wheel, a cam shaft mounted in said bridge member and co-operating with all units in a head and means operative upon said cam shaft to permit movement of said pawls.

In witness whereof I have hereunto affixed my signature this 2d day of November, 1929. 100
JAMES H. REINHARDT.
